UNITED STATES PATENT OFFICE

ROBERT H. McWILLIAMS, OF MEMPHIS, TENNESSEE

RAILROAD SYSTEM FOR LEVEE CONSTRUCTING

Application filed July 11, 1928. Serial No. 291,849.

My said invention relates to a system for constructing levees and it is an object thereof to provide improved means for handling dump cars used in such construction or in 5 other analogous situations.

Referring to the drawings, which are made a part of this application and in which similar reference characters indicate similar parts:

- 10 Fig. 1 is a cross section of a levee,
- Fig. 2, a plan of the same, showing my improvements as applied thereto,
- Fig. 3, a detail of the tracks for dump cars,
- Fig. 4, a longitudinal section showing 15 different positions of a portion of a dump car and of a power car used in connection therewith,
- Fig. 4^a, a transverse section of a part of the track,
- 20 Fig. 5, a plan on an enlarged scale of elevating mechanism for the dump cars, and
- Fig. 6, a similar view of lowering mechanism.

In the drawings reference character 10 indicates the top of a levee which it is proposed to improve, the incline at the river side being indicated at 11, the proposed incline at the land side at 12, the present incline at the land side at 13 and the outline of the reinforcement 25 at 14. A banquette 15 provides a level space adjacent the top of the levee for a track 16 on which trains may run as indicated in Fig. 2 and a track 17 runs more or less approximately parallel to the first named track and 30 to the levee along the river bank. Tracks 18 and 19 connect the tracks 16 and 17, the tracks 18 and 19 running on the approximately level ground between the river and the levee and then continuing up the relatively steep incline of the levee to the track 16. Trains of dump cars operate on the various 35 tracks for moving from the barrow pits 20 to the top of the levee and along the track 16 to the desired position for dumping, steam shovels 21 or other desirable loading means 40 being provided adjacent the barrow pits for loading the cars and the trains being drawn by locomotives along tracks 16 and 17 and the relatively level parts of tracks 18 and 19.

50 I provide means to aid the locomotives in

pulling the trains up the sides of the levee and for controlling the downward movement on tracks 18 and 19 at such points.

The means for assisting in the elevation of the trains comprises a hoist 21' operated by an engine 22 connected in driving relation to a drum 23 about which a portion of a cable 24 is wound. The cable passes above a pulley 25 on a support 26 here shown as located between the rails of the track 16 and thence to a power car 27 having wheels 28 running on rails of an auxiliary track 29 positioned between the rails of the track 19. The track 29 has an inclined part at 30 at a point spaced from the river side of the levee and runs then at a lower level as indicated at 31 for a distance at least sufficient to permit the power car to assume such a low position that the train can pass above the power car without touching it, the parts 30 and 31 being preferably at such a distance from the side of the levee as to permit the entire length of the train to pass beyond the part 30 before the train starts up such side. The depressed part of the tracks 31 is supported on ties 32 which may be sunk more deeply than the ties supporting the elevated portions, blocks 33 being provided for supporting the rails 19 in appropriate position. Obviously other means may be employed for this purpose.

In Fig. 4 I have illustrated the operation of the power car, the left-hand position showing the power car below an axle 35, which may be the rear axle of the rear-most dump car mounted on wheels 34. The power car has an upward extension 33 on the body 27 adapted to engage the axle 35 for pushing the train. The intermediate position in Fig. 4 illustrates the power car riding up the incline 30 toward its position for engaging the axle 35 and the right-hand position illustrates the projection 33 as being in engagement with the axle.

A track 36 is shown in Fig. 6 at one side of the main track 18, this track like the auxiliary track 29 extending only down to the relatively level ground at the foot of the levee or approximately so far. A power car 37 has wheels 38 running on a track 39 similar to the track 29 and having similar inclined

and depressed portions. A cable 40 extends from the power car around a pulley 41, then about a drum 42, about another pulley 43 and thence to a counter-balancing car 44 on track 36.

In the operation of my device one or more trains may be loaded simultaneously at different positions on the track 17 and may then be moved along the track 19 to the bottom 10 of the levee, where they pass over the power car 27 on the depressed portion 31 of the auxiliary track, after which the hoist is operated to move the power car into the different positions indicated in Fig. 4 and then 15 to assist the movement of the train by its locomotive up the steeply inclined part of track 19. Preferably, though not necessarily, the track on the side of the levee is laid at an acute angle to the track 16 so as 20 to decrease the grade up which the train must be drawn. After the trains reach the tracks 16 they may be moved in either direction thereon to the point where they are to be dumped, after which they can be moved 25 to one of the tracks 18. The power car on the track 18 is normally in position at the highest part of the track 18, as indicated in Fig. 6, so as to be in position to engage the rear axle of the rear-most car and control 30 the descent of the train through the action of the counter-balancing car 44 which is heavier than the power car 37. The difference in weight is for the purpose of retarding the train of empties and for the additional purpose of returning the power car to 35 its highest position after each lowering operation. The cable 40 connecting the two cars is wound about the drum 42 which may be provided with suitable braking means indicated 40 at 49 for the purpose of additionally retarding the lowering movement of the train. At the bottom of the grade the power car moves into a depressed position in such a manner as illustrated in Fig. 4 or in any other suitable 45 manner and permits the train to ride over it under the control of its locomotive. Preferably the auxiliary track 39 and the connecting track 18 are at such an angle to the track 16 as above described for track 19 and for 50 similar reasons. The track 36 extends only to the bottom of the grade or a little further to provide for movement of the counter-balancing car corresponding to that of the power car 37. Two or more trains can use the elevating track 19 for elevating each train of 55 cars and its locomotive as they are loaded at the separate barrow pits. It will be understood that no counter-balancing car is needed for the power car 27 as mere release of the 60 hoist permits this power car to return to position for engagement with the next train. Two trains can be lowered on the lowering track and one raised on the elevating track 65 at the same time if desired.

It will be obvious to those skilled in the art

that various modifications may be made in my device without departing from the spirit of the invention and therefore I do not limit myself to what is shown in the drawings and described in the specification but only as indicated in the appended claims. 70

Having thus fully described my said invention, what I claim as new and desire to secure by Letters Patent, is:

1. The combination in a railroad system 75 for levee construction, of a track extending along the levee adjacent the top of the same, an approximately parallel track adjacent the levee, a track connecting the first and second tracks, power means in connection with said connecting track for elevating a train, a fourth track adjacent the third track also connecting the first and second tracks, and means in connection with said fourth track for keeping a train under control while being 80 lowered along the same.

2. The combination in a railroad system 85 for levee construction, of a track extending along the levee adjacent the top of the same, an approximately parallel track adjacent the levee, a track connecting the first and second tracks, and power means in connection with 90 said connecting track for elevating a train.

3. The combination in a railroad system 95 for levee construction, of a track extending along the levee adjacent the top of the same, an approximately parallel track adjacent the levee, a track connecting the first and second tracks, power means in connection with said connecting track for elevating a train, said 100 power means comprising a power-operated car adapted to engage said train, and means arranged to bring the power car into engagement with the train when the train reaches a predetermined point on its way up the 105 levee.

4. The combination in a railroad system 110 for levee construction, of a track extending along the levee adjacent the top of the same, an approximately parallel track adjacent the levee, a track connecting the first and second tracks, power means in connection with said connection track for elevating a train, said 115 means comprising a power-operated car adapted to engage said train, and an auxiliary track for the power car between the rails of the track for the train, said auxiliary track being depressed at the bottom of said grade to permit the train to pass over the power car before being engaged thereby.

5. The combination in a railroad system 120 for levee construction, of a track extending along the levee adjacent the top of the same, an approximately parallel track adjacent the levee, a track connecting the first and second tracks, power means in connection with said connecting track for elevating a train, said power 125 means comprising a power-operated car adapted to engage said train, an upward projection on said power car, and means arranged 130

to bring the projection into engagement with the axle of a car of said train when said train reaches a predetermined point on said track.

5 6. The combination in a railroad system for levee construction, of a track extending along the levee adjacent the top of the same, an approximately parallel track adjacent the levee, a track connecting said first and second tracks, and means in connection with said tracks for keeping a train under control while being lowered along the same.

10 7. The combination in a railroad system for levee construction, of a track extending along the levee adjacent the top of the same, an approximately parallel track adjacent the levee, a track connecting said first and second tracks, means in connection with said tracks for keeping a train under control while being lowered along the same, said means comprising a power car adapted to engage a descending train, and means to resist the downward movement of the power car.

15 8. The combination in a railroad system for levee construction, of a track extending along the levee adjacent the top of the same, an approximately parallel track adjacent the levee, a track connecting said first and second tracks, means in connection with said tracks for keeping a train under control while being lowered along the same, said means comprising a power car adapted to engage a descending train, and means to resist the downward movement of the power car combined with means for automatically disengaging said power car from said train at a predetermined time.

20 9. The combination in a railroad system for levee construction, of a track extending along the levee adjacent the top of the same, an approximately parallel track adjacent the levee, a track connecting said first and second tracks, means in connection with said tracks for keeping a train under control while being lowered along the same, said means comprising a power car adapted to engage a descending train, an upward projection on said power car adapted to engage an axle on a car of a descending train, and means to resist the downward movement of said power car.

25 10. The combination in a railroad system for levee construction, of a track extending along the levee adjacent the top of the same, an approximately parallel track adjacent the levee, a track connecting said first and second tracks, means in connection with said tracks for keeping a train under control while being lowered along the same, said means comprising a power car adapted to engage a descending train, an upward projection on said power car adapted to engage a car axle, and means arranged to disengage the projection from such axle at a predetermined point on the track.

30 11. The combination in a railroad system for levee construction, of a track extending

along the levee adjacent the top of the same, an approximately parallel track adjacent the levee, a track connecting said first and second tracks, means in connection with said tracks for keeping a train under control while being lowered along the same, said means comprising a power car adapted to engage a descending train, a counter-balancing car connected to said power car, and a track for said counter-balancing car.

35 12. The combination in a railroad system for levee construction, of a track extending along the levee adjacent the top of the same, an approximately parallel track adjacent the levee, a track connecting said first and second tracks, means in connection with said tracks for keeping a train under control while being lowered along the same, said means comprising a power car adapted to engage a descending train, a counter-balancing car connected to said power car, a track for said counter-balancing car, a cable connecting said cars, a drum about which said cable is wound between said cars, and braking means for said drum.

40 13. The combination in a railroad system for levee construction, of a track extending along the levee adjacent the top of the same, an approximately parallel track adjacent the levee, a track connecting said first and second tracks, means in connection with said tracks for keeping a train under control while being lowered along the same, said means comprising a power car adapted to engage a descending train, a track for said power car between the rails of the connecting track, and means for controlling the movement of the power car.

45 14. The combination in a railroad system for levee construction, of a track extending along the levee adjacent the top of the same, an approximately parallel track adjacent the levee, a track connecting said first and second tracks, means in connection with said tracks for keeping a train under control while being lowered along the same, said means comprising a power car adapted to engage a descending train, a counter-balance for said power car, and means for automatically disengaging said power car from said train at a predetermined time.

In testimony whereof I affix my signature.
ROBERT H. McWILLIAMS.
